STOKER

Nathan M. Lower, Erie, Pa., assignor to The Standard Stoker Company, Incorporated, a corporation of Delaware

Application June 17, 1937, Serial No. 148,675

5 Claims. (Cl. 110—105.5)

This invention relates to stokers employing air as the vehicular agent for transporting fuel from a source of supply and for distributing it within a furnace.

5 In stokers of the type to which reference has been made, the vehicular air is usually generated by a fan, and, in order that the fuel particles may be suspended or "floated" through the conduit by the air stream, it is necessary that a 10 high velocity of the air be attained. Introduction of this vehicular air at high velocities into the furnace results in supplying the fire with air considerably in excess of actual combustion requirements. Thus, the predetermined draft of 15 the furnace is adversely affected and the temperature within the furnace lowered. Furthermore, while the high vehicular air velocity is necessary for transmitting the initial impetus to the fuel, it is not desirable to introduce the 20 fuel into the furnace at high velocities because the greater amount of the fuel is deposited at the forward end of the furnace, resulting in improper distribution of the fuel over the fire.

The present invention seeks to overcome the 25 difficulties of past practices, and accordingly, this constitutes the main object of this invention.

More specifically, it is an object of this invention to provide, in a stoker employing swiftly 30 moving currents of air for transporting fuel to and depositing it within a furnace, means for reducing the velocity of the air currents to the end that the fuel may be distributed evenly over the firebed.

35 In carrying out this object, and as a further object of my invention, I provide means for withdrawing the vehicular air from the stoker delivery conduit prior to any substantial admission of such vehicular air into the furnace, thereby 40 avoiding undesirable furnace draft conditions which would otherwise obtain should great quantities of excess air be admitted into the furnace.

It is also an object of this invention to recirculate the vehicular air so withdrawn and utilize 45 it over and over again as the agent for carrying the fuel into the furnace. Preferably, this air is caused to be recirculated adjacent the furnace, whereby any vehicular air entering the furnace is heated and results in improved combustion efficiency.

A still further object of this invention resides in the provision of means for heating the vehicular air, such means being thermostatically controlled and arranged to entrain hot gases from

within the furnace and into the vehicular air stream.

Another object of this invention resides in providing a novel arrangement for withdrawing the vehicular air from the fuel discharge or delivery conduit, such arrangement consisting of an air return conduit at each side of the stoker discharge conduit, one end of such air return conduit being in communication with the discharge conduit and the opposite end thereof communicating with the intake side of a fan which generates the swiftly moving stream of air.

It is also an object of this invention to provide novel means for deflecting fine and lump fuel as it is propelled through the stoker conduit.

Other objects, such as the provision of a pair of fans, one at each side of the stoker conduit, which fans are arranged for conjoint operation by a single prime mover, will become apparent as the following specification is read in connection with the accompanying drawings illustrating the invention as embodied in a locomotive and tender.

Fig. 1 of these drawings is a vertical medial section through adjacent portions of a locomotive and tender with the invention in side elevation, parts of which have been broken away;

Fig. 2 is a plan view taken on the line 2—2 of Fig. 1 with portions removed and other portions broken away;

Fig. 3 is a sectional view taken on the line 3—3 of Fig. 2;

Fig. 4 is an elevation of the structure shown in Fig. 2 as viewed along the line 4—4 thereof;

Fig. 5 is a sectional view taken on the line 5—5 of Fig. 2;

Fig. 6 is a view similar to Fig. 2 illustrating a modification;

Fig. 7 is a side elevation of the structure shown in Fig. 6;

Fig. 8 is a sectional view taken on the line 8—8 of Fig. 6; and

Fig. 9 is a sectional view taken substantially on the line 9—9 of Fig. 6 with portions broken away.

Referring now to Figures 1 to 5, inclusive, L indicates a locomotive having a furnace of firebox 10 supported above the frame 11. The firebox 10 includes a hollow backwall 12 having a firing opening 13 disposed above the level of the grates 14 and the cab deck 15. Coupled to the locomotive at C is a tender T having a tank 16 supported upon a frame 17. The tank includes a water compartment 18 and a fuel bin 19 disposed above the floor 20. The stoker for transferring fuel from the bin 19 and into the firebox 10

10 is shown at S and includes a trough 21 mounted on the frame 17 beneath the bin 19 and a tubular conduit 22 universally connected at 23 with the trough and at 24 with the fuel 5 delivery or discharge conduit 25. The trough 21 has mounted therein a crusher 26 against which large lumps of fuel are urged by a conveyor screw 27 and broken down to a suitable size. Crushed fuel is then urged forwardly by the conveyor screws 28, the latter being disposed within the tubular conduit 22 and supplying fuel at a suitable rate to the discharge conduit 25. A motor 29 transmits power for operating the screws 27, 28 through shafting 30 and gearing 15 which is encased in a housing 31 at the rear of the trough 21.

The fuel discharge conduit 25 includes an upright tube 32, the lower end of which is closed by trap door 33 while its upper end has seated thereon an elbow 34 which curves into the lower portion of the firing opening 13. Intermediate its upper and lower ends, the upright tube 32 is provided with an opening 35 through which crushed fuel is supplied by the conveyor screw 25 28. The fuel supplied into the upright tube 32 is propelled into the firebox 10 by swiftly moving currents of air which are generated by a fan 36 secured to the frame 11 at one side of the discharge conduit 25. A turbine V supplies the 30 motive power for operating the fan 36 at a rate of speed sufficient to insure propulsion of the fuel through the discharge conduit 25 in a fluid-like stream. The fan 36 receives air axially thereof through an opening 37 which communicates with 35 a duct 38.

Air is discharged by the fan 36 through a flexible coupling 39 which opens into the lower portion of the upright tube 32. Any foreign material in the fuel which is too heavy to be lifted 40 by the air stream remains within that portion of the tube 32 below the opening 35 and may be removed upon opening of the trap door 33. As the fuel is supplied into the tube 32, the swiftly moving currents of air generated by the fan 36 45 propel the fuel upwardly and thence forwardly through the elbow 34 into the firebox 10.

In stokers of the type herein described, the finer particles of fuel travel along the top wall 40 of the elbow 34 while the heavier lumps are propelled along the bottom wall 40a. Lateral distribution of fine fuel is effected by means of a deflector member 42 which is pivoted with respect to the top wall 40 for movement about the axis of the vertical pin 43. The top wall 40 is 55 also pivotally mounted for movement about the transversely extending pin 41 whereby the deflector member 42 may intercept varying quantities of fine fuel for lateral distribution. Likewise, means are provided for distributing laterally the lump fuel as it is propelled along the bottom wall 40a of the elbow 34. For this purpose, a deflector member 9 is provided at 8 to swing about a horizontal axis extending transversely of the locomotive whereby the deflector member 9 may intercept varying quantities of lump fuel for lateral distribution. Suitable means 7 may be utilized to effect adjustment of the deflector member 9 about its pivot 8.

The oxygen necessary to support combustion 70 within the firebox is supplied by entraining air upwardly through the grates which are provided with openings adequate in size to insure the admission of sufficient air. In the case of a locomotive rebox, the air is entrained into the 75 firebox by creating a sub-atmospheric pressure

condition therein whereby the air at atmospheric pressure will enter through the openings of the grates. This sub-atmospheric pressure condition is due to the exhaust of steam passing through the locomotive stack (not shown) which 5 is in communication with the firebox.

When once determined, the drafting of the firebox or furnace should rarely be altered, as to do so results in combustion inefficiencies. In the use of air as vehicular agent for introducing fuel 10 into a furnace, it is concomitant that air greatly in excess of actual combustion requirements is supplied over the firebed. This results in lower combustion rates because the vehicular air occupies space within the furnace necessary for 15 the gases of combustion. It has been proposed to use, instead of grates having the usual openings and provisions for shaking these grates, flat plates with greatly restricted air openings for supporting the firebed, the vehicular air used to 20 propel the fuel into the furnace being utilized to supply the additional oxygen necessary for combustion. However, this requires considerable change in the drafting arrangement for the furnace, and, furthermore, since the customary 25 movable grates are not used, it is necessary to shut down operation of the furnace at times when it is necessary to clean the fire.

In accordance with the objects of this invention, I overcome the difficulties of past practices by providing means for withdrawing the vehicular air prior to any substantial admission thereof to the furnace or firebox 10. To carry out this object, the side walls 45, 46 of the elbow 34 are each provided with a series of slots 47 35 establishing communication between a chamber 48, 49 at one side of a respective side wall 45, 46 and the interior of the elbow 34. The slots 47 are directed forwardly into fuel discharge conduit 25 and are spaced closely together in order 40 to prevent withdrawal of any substantial amounts of fuel back into the fan 35. The chambers 48, 49 are connected by tubes 50, 51, respectively, to a duct 38 which extends transversely of the locomotive and is disposed between 45 the backwall 12 and the discharge conduit 25. One end of the duct 38 is in communication with the axial intake opening 37 of the fan 36 while its opposite end has mounted therein a manually operable valve 53 for controlling the 50 admission of air into the duct 38. Normally, the valve 53 is in the position shown in Fig. 5 allowing but a slight amount of air to enter the duct 38.

Hot gases from within the firebox 10 are entrained into the duct 38 by a pipe 54 which opens 55 into the firebox below the firing opening 13. A valve 55 is disposed within the pipe 54 and it is operated by means of a lever 56, the movement of which is controlled by a thermostat 57. The 60 thermostat 57 is responsive to the temperature within the duct 38 and controls the valve 55 in a manner whereby a predetermined temperature is maintained within the duct 38 during operation of the locomotive. Preferably, the thermostat is so regulated that the temperature within the duct 38 is below the fusing point of 65 the fuel.

In the operation of this form of the invention, fuel crushed by the conveyor screw 27 and 70 the crusher 26 is urged forwardly by the screw 28 through the opening 35 and enters the swiftly moving air stream within the discharge conduit 25. Fuel is thus propelled upwardly and thence forwardly through the elbow 34. Distribution of 75

the propelled fuel over the grates 14 is effected by means including the deflector members 42 and 49.

Since the fuel as supplied to the discharge conduit 25 contains lumps as well as fine particles, it is necessary that the fan 36 generate a stream of air sufficiently powerful so that an initial high velocity may be imparted to the lumps. While this high velocity of the vehicular air is essential, it has been found to be a factor which adversely affects proper distribution of fuel over the grates for the reason that the greater bulk of fuel is deposited at the forward end of the firebox. In the present invention, the greater part of the swiftly moving vehicular air, as it propels the fuel through the elbow 34, is withdrawn into the duct 38 through the slots 47 and chambers 48, 49. The vehicular air so withdrawn enters the intake opening 37 of the fan 36 and is thus utilized over and over again as an agent for propelling the fuel into the firebox 10. Additional air may be supplied to the duct 38 through proper manipulation of the valve 53. When the vehicular air is so withdrawn from the elbow 34, it will be apparent that the high initial velocity imparted by the fan to the fuel stream is lowered a considerable extent. This results in more uniform distribution of lump and fine fuel particles over the entire firebed. Furthermore, very little, if any, vehicular air will enter the firebox due to the entrainment feature. In this manner, an undesirable amount of excess air is not supplied into the furnace.

Since the vehicular air is utilized over and over again, great quantities of excess air are not introduced into the firebox resulting in more stable drafting conditions. Furthermore, with the recirculation of the vehicular air adjacent the firebox 10, what small quantity of air may enter the firebox is heated to a high degree and thereby does not act to reduce firebox temperatures. The hot firebox gases are entrained into the duct 38 through the thermostatically controlled pipe 54. In this manner, fine coal is heated substantially throughout its entire volume so that upon entering the firebox it will ignite almost instantaneously. This insures complete combustion of fine fuel particles and this eliminates excessive loss of unburned fuel through the stack.

In the modification illustrated in Figures 6 to 9, inclusive, a pair of fans 60, 61, one at each side of the stoker conduit 22, is provided for propelling fuel through the discharge conduit 25. The use of two fans will be found to be of advantage when larger fuel lumps are used or when higher delivery rates are to be maintained. Conversely, the use of a pair of fans, in place of the single fan as shown in Figures 1 to 5, inclusive, will result in the use of smaller fans, which may be more readily installed on smaller locomotives than would otherwise be possible.

A turbine V' operates the fans 60, 61 through a shaft 52 which passes beneath the conduit 22. Each fan 60, 61 is provided with an air intake duct 62, 63 having communication through ducts 64, 65 with a chamber 48, 49, respectively, at each side wall of the discharge elbow 34. The output of each fan 60, 61 is conducted through a duct 66, 67, respectively, each of which opens into the lower end of the discharge conduit 25. As in the preferred form, the vehicular air passing into the discharge conduit 25 propels the fuel upwardly and forwardly through the elbow 34

into the firebox 10. Slots 47 in each side wall 45, 46, are utilized for withdrawing the vehicular air from the elbow 34 to the air intake duct 62, 63 whereby it may be recirculated. In all other respects, this form of the invention functions in precise accordance with the preferred form.

While the invention is primarily concerned with the introduction of fuel by vehicular fluid to a furnace, it will be obvious that certain features of this invention are of general application.

From the foregoing descriptions, those familiar with the art will readily understand that the stated objects of this invention have been attained by the construction described and now to be claimed.

I claim:

1. In a stoker for a furnace, a conduit leading to the furnace from a source of fuel supply, a fan outside said conduit arranged to discharge an air stream into said conduit remote from the fuel discharge end thereof for propelling fuel therethrough and projecting it in aerial paths over the firebed in said furnace, said conduit being provided in its wall for a substantial distance rearwardly from its discharge end with a plurality of apertures, said apertured wall portion being disposed with respect to the direction of travel of the fuel through the conduit to prevent impingement of fuel thereagainst, and means forming a passage from said apertured wall portion to the intake side of said fan for withdrawing air from the air stream in said conduit.

2. In a stoker for a furnace, a conduit leading to the furnace, a fan outside said conduit arranged to discharge an air stream into said conduit at that end thereof remote from the furnace, said conduit having a fuel receiving opening between its ends communicating with a source of fuel supply whereby the fuel is propelled through said conduit and projected in aerial paths over the firebed in said furnace, said conduit being provided in its wall for a substantial distance rearwardly from its discharge end with a plurality of apertures, said apertured wall portion being disposed with respect to the direction of travel of the fuel through the conduit to prevent impingement of fuel thereagainst, and means forming a passage from said apertured wall portion to the intake side of said fan for withdrawing air from the air stream in said conduit.

3. In a stoker for a furnace, a conduit leading to the furnace from a source of fuel supply, a fan outside said conduit arranged to discharge an air stream into said conduit remote from the fuel discharge end thereof for propelling fuel therethrough and projecting it in aerial paths over the firebed in said furnace, said conduit being provided in its wall for a substantial distance rearwardly from its discharge end with a plurality of apertures, said apertures being directed inwardly and toward the discharge end of the conduit, said apertured wall portion being disposed with respect to the direction of travel of the fuel through the conduit to prevent impingement of fuel thereagainst, and means forming a passage from said apertured wall portion to the intake side of said fan for withdrawing air from the air stream in said conduit.

4. In a stoker for a furnace, an elbow shaped conduit including a horizontal discharge portion and an upstanding portion depending from the rearward end of said horizontal portion, said conduit having a fuel receiving opening in its upstanding portion, a fan outside said conduit ar-

- ranged to discharge an air stream into the lower end of said upstanding conduit portion for propelling fuel through said conduit and projecting it in aerial paths over the firebed in said furnace, the horizontal conduit portion being provided in its wall with a plurality of apertures, said apertured wall portion being disposed with respect to the direction of travel of the fuel through the conduit to prevent impingement of fuel thereagainst, and means forming a passage from said apertured wall portion to the intake side of said fan for withdrawing air from the air stream in said conduit.
5. In a stoker for a furnace, a conduit leading to the furnace from a source of fuel supply, a fan outside said conduit arranged to discharge a gaseous stream into said conduit remote from the fuel discharge end thereof for propelling fuel
- 10 therethrough and projecting it in aerial paths over the firebed in said furnace, said conduit being provided in its wall for a substantial distance rearwardly from its discharge end with a plurality of apertures, said apertured wall portion being disposed with respect to the direction of travel of the fuel through the conduit to prevent impingement of fuel thereagainst, means forming a passage from said apertured wall portion to the intake side of said fan for withdrawing gases from the gaseous stream in said conduit, and means forming a passage communicating at one end with the combustion chamber of said furnace and at its other end with the intake side of said fan for entraining products of combustion 15 from said furnace.

NATHAN M. LOWER.
